CLAIM

The ornamental design for retractable ear buds with crystal design, as shown and described.

DESCRIPTION

FIG. 1 is a perspective view of retractable ear buds with crystal design showing my new design, the undisclosed portions are not part of the claimed design;

FIG. 2 is a top plan view of the invention;

FIG. 3 is a bottom plan view of the invention;

FIG. 4 is a left-side elevational view of the invention;

FIG. 5 is a right-side elevational view of the invention;

FIG. 6 is a rear elevational view of the invention; and,

FIG. 7 is a front elevational view of the invention.

The broken lines in FIG. 3 are included for the purpose of illustration and form no part of the claimed design.
